SLUG CASTING MACHINE

Richard E. Mead, Queens Village, N. Y., assignor
to Mergenthaler Linotype Company, a corpora-
tion of New York

Application April 11, 1936, Serial No. 73,847

20 Claims. (Cl. 199—50)

This invention relates to slug casting machines, such as Linotype machines of the general organization represented in United States Letters Patent to O. Mergenthaler No. 436,532, wherein circulating matrices and expansible spacebands are composed in line by the manipulation of a keyboard, the composed line transferred to a slotted mold for the casting of a type bar or slug, and the matrices and spacebands thereafter separated and returned by a distributing mechanism to the magazines from which they started. More particularly, the invention relates to machines of this character equipped with quadding and centering devices, in order that the machine may handle not only lines of full length as ordinarily, but in addition lines of less than full length (regardless of their actual length), lines of the latter kind in machines of this character being composed merely with the matrices necessary for the printed matter and indented at the left or at the right end of the line or centered as desired.

A machine so constructed is disclosed in the Frolander Patent No. 1,971,400. In the machine therein disclosed, the movable supports for the two line clamping jaws (the latter being made long enough to perform their required functions of closing the mold slot at the front) are actuated through two distinct trains of connections from a vertically movable member controlled from the main shaft of the machine. When both jaw supports are connected to the member, they are, prior to casting, moved equidistantly toward each other until arrested by the contact of their respective jaws with the opposite ends of the composed line (for centering) and later, after casting, restored to their original positions of maximum separation. Due provision is made for disconnecting either the right hand jaw or the left hand jaw from the vertically movable member, so that one or the other may be operated independently for quadding at the right or at the left as may be desired. When both jaws are disconnected as they may be, the machine is free to function in the usual way, the right hand jaw being left normally stationary and the left hand jaw being adjustable by the customary devices.

When the clamping jaws are moved into contact with the composed line, the vertically movable member is locked in its downwardly moved position by means of a toggle clamp actuated by a lost motion device included in the operating connections for the member and, after a casting operation, the toggle clamp is released, allowing

the vertically movable member to ascend and restore the clamping jaws to their positions of maximum separation. It has been found that if the pressure exerted by the line clamping jaws is suddenly released, either by the rapid backing off of the jaws in moving to their normal positions of maximum separation or by the removal of the line from between the jaws prior to the release of the clamping pressure exerted by the latter, there is a tendency for the matrices in the line, due to the sudden release of the clamping pressure, to spring out endwise.

To obviate this condition, it is proposed in accordance with the present invention, to back off the jaws slightly from the composed line after the casting operation to relieve the line clamping pressure and to maintain the jaws in their slightly backed off positions until the line, by the ascent of the line transporter, has been carried upwardly clear of the jaws. Another advantage of this construction resides in the fact that the end matrices will be wiped by the jaws as the line is carried from between them, thus removing any metal that may have adhered thereto during the casting operation.

In accordance with the present improvements, the toggle clamp, which ordinarily comprises a block operated by a toggle device for holding the vertically movable member in its downward position, is allowed a limited degree of movement while still in engagement with the vertically movable member to allow the latter to be actuated upwardly for a small distance to permit the slight backing off of the line clamping jaws before the line has been lifted clear of the jaws, the toggle clamp being disengaged from the vertically movable member after the line has cleared the jaws to permit the vertically movable member to ascend to its uppermost position and return the jaws to their positions of maximum separation.

These and other features of the invention will be fully set forth in the detailed description to follow.

Referring to the drawings:

Fig. 1 is a front elevation of a portion of a Linotype machine equipped with the present improvements;

Fig. 2 is an end elevation of certain of the parts shown in Fig. 1, looking from the left in that figure;

Fig. 3 is a plan view of certain of the parts shown in Fig. 2;

Fig. 4 is a horizontal section through the first elevator and vertically movable member just above the toggle clamp housing;

Fig. 5 is a vertical section on the line 5—5 of Fig. 4;

Figs. 6 and 7 are perspective views of certain detail parts of the toggle clamp mechanism;

5 Fig. 8 is a vertical sectional view through a portion of the toggle clamp block;

10 Fig. 9 is a view similar to Fig. 2, with some of the parts omitted however and with the parts shown at a different phase of the machine cycle of operation; and

15 Fig. 10 is a front view of some of the parts shown in Fig. 1, but at a different phase of the machine cycle of operation.

The matrices X and the expandable spacebands 20 Y, after being composed in line in the assembler in the usual way, are transferred to a vertically movable transporter or first elevator A slidably mounted in the fixed vise frame B. Upon receiving the line, the first elevator immediately 25 descends to position it between the left hand jaw E and the right hand jaw F (Fig. 1) and in front of a slotted mold (not shown), which latter then advances from the rear and into contact with the line and the two clamping jaws 30 for the slug casting operation, the line, prior to casting, being alined and justified in the usual way when the machine is being operated under the usual conditions. After the slug has been cast, the mold is carried from its horizontal casting position to a vertical ejecting position by a three-quarter rotation of the mold disc, the first elevator in the meantime being raised to deliver the composed line to the matrix and spaceband distributing devices and finally coming to rest in 35 its original or line receiving position.

As described in the Frolander patent previously referred to, the two jaws E and F are mounted for movement in the vise frame in the customary manner, being carried by supporting blocks E¹ and 40 F¹ slidable in suitable guideways in the vise frame and are movable toward and from each other by a periodically operated part in the form of a vertically movable rod H which may be connected at its upper end to the respective jaws 45 through the medium of two similar but oppositely disposed bell crank levers E² and F² pivoted at E³ and F³ to the vise frame, the longer arms of said levers being connected by short links E⁴ and F⁴ to the jaw supports E¹ and F¹, respectively, and the shorter arms of said levers being arranged for connection to the rod H. According 50 to this arrangement, when the rod H is moved downwardly from its uppermost position (which is its normal position of rest), it will move the two jaws equidistantly toward each other (assuming both to be connected to the rod) until they contact with the opposite ends of a composed line which has previously been positioned between them and, when the rod is moved upwardly for restoration to its position of rest, it will in like manner move the jaws equidistantly away from each other to return them to their original positions of maximum separation. Since 55 the composed line positioned between the jaws may vary in length, the actual extent of movement of the rod H will, of course, vary accordingly, and hence provision is made for such varied movement of the rod in its actuating connections, as will presently appear.

70 Suitable provision, in the nature of a segmental grooved member H¹, is made at the upper end of the vertically movable rod H for connecting the jaws thereto, this grooved member being adjustable so as selectively to connect 75 either or both jaws to the rod as desired for quad-

ding at either end of the line or for centering. The manner in which the member is adjusted has no concern with the present invention and nothing further will be said about it here.

The rod H is slidable in suitable bearings, only 5 one B¹ of which is shown, in the fixed frame. At its lower end, the rod H is connected by a link H² to the forward end of a lever H³ having a hub portion H⁴ journaled on a pivot rod H⁵ carried by a bracket (not shown) secured to the 10 vise frame (Figs. 1, 2 and 3). Fixed to and depending from the hub portion H⁴ is a barrel or cylinder H⁶ containing an expansion spring H⁷ pressing upwardly against a lug H⁸ projecting forwardly from the hub portion of a second lever 15 H⁹ also journaled on the pivot rod H⁵. The lifting tendency of the spring H⁷ is resisted and overcome by the engagement of a stop lug H¹⁰ on the hub portion of the second lever H⁹ with a stop lug H¹¹ formed on the hub portion of the 20 first lever H³, the effect of this arrangement being to cause the two levers to move in unison until the first lever is arrested by the rod H as the jaw or jaws, whichever is connected thereto, banks against the composed line.

25 The second lever H⁹ is connected at its rear end by the roller and groove connection H¹² to the forward end of a bent lever H¹³ journaled on a pivoted rod H¹⁴ fixed in the main frame, a tension spring H¹⁵ being connected to the lever in advance of its pivot and serving constantly to move it downwardly at its forward end. The lever at its rear end is provided with a roller H¹⁶ tracking upon the periphery of an edge cam M¹ fast to the main shaft M of the machine.

30 From the foregoing construction, it will be seen that the rotation of the cam M¹ (which is always in a clockwise direction and which makes one complete rotation at each cycle of operation of the machine) is imparted to the rod H, through the train of connections just described, to move the rod first downwardly to effect the inward or closing movement of the jaws E and F, and then upwardly to effect the outward or separating movement of the jaws. Since, as already stated, 35 the downward movement of the rod H will vary according to the length of the composed line positioned between the jaws, its actuating connections must be arranged to yield as the rotation of the cam continues, and this yielding is provided for by the lost motion which takes place between the two levers H³ and H⁹, the latter acting on the former through the expansion spring H⁷ which, of course, will be compressed to absorb the lost motion. The lever H⁹, being thus 40 permitted to partake of a full rocking movement, may be (as it is) positively connected to the cam operated lever H¹³.

45 The downward or jaw closing movement of the rod H takes place as the roller H¹⁶ runs from the low portion onto the high portion of the cam M¹, while the upward or jaw separating movement of the rod H takes place after the roller has passed the high portion of the cam at a point in the machine cycle hereinafter to be noted. The roller H¹⁶ is urged in contact with the rotary cam by the spring H¹⁵, but it will not be allowed to pass from the high portion of the cam to the low portion of the cam at the point where the former terminates, but at a somewhat later period in the machine cycle for reasons hereinafter set forth. It may be noted here that the high and low portions of the cam are such that the jaws will be closed before and held closed during the 50 slug casting operation, and in the other case 55 60 65 70 75 80 85 90 95 98 99 100

separated and held separated between successive slug casting operations.

In order to lock the rod H in its downwardly moved position, there is provided a toggle member 5 J (see Fig. 5) enclosed within a box or housing B² which carries the bearing B¹ before alluded to. This toggle member operates a clamp or grip element J¹ arranged to contact with a sleeve H¹⁷ carried by the rod H and which, for purposes of 10 the present description, may be assumed to be integral with the rod H. Associated with the toggle is an actuating link J² provided at its upper end with an adjusting screw J³ arranged to bear upon the toggle joint. At its lower end, the link 15 J² is connected by a turn buckle link J⁴ to the forward upwardly bent arm of the lever H⁹ before referred to. As will be noted in Fig. 5, the link is slotted as at J⁵, so as to straddle the toggle joint, being encircled within the box by a compression spring J⁶ which normally presses upwardly through a pin or stud J⁷ on the toggle joint to maintain the grip element J¹ in inactive position.

It will now be seen that the toggle member J 25 is operated by reason of the lost motion which takes place between the two levers H³ and H⁹, it being remembered that the former lever is the one connected to the rod H. In other words, after the lever H³ is arrested in its movement by the 30 cessation in downward movement of the rod H (due, of course, to the contact of the jaws E and F with the opposite ends of a composed line), the lever H⁹ continues to move to its full extent under the influence of the rotary cam M¹, acting 35 in the meantime to continue its drawing down of the link J². The length of the link (or what amounts to the same thing, the position of the screw J³ thereon) is such that during the last portion of the movement of the lever H⁹, the screw 40 is moved within the box and caused to actuate the toggle member J so as thereby to press the grip element J¹ under heavy pressure against the sleeve H¹⁷ and lock the rod H securely in its downwardly moved position.

Actually, the rod H and its sleeve H¹⁷ are not connected together as one, provision being made for a slight relative movement between the rod and the sleeve after the latter has been locked by the toggle member in the downwardly moved or 45 line clamping position of the rod in order to allow for a limited line spread during justification. Referring particularly to Figs. 1 and 5, it will be noted that at its lower end, the rod H is provided with a fixed collar h threaded on the rod and 50 which contains an expansion spring h¹ encircling the rod H and pressing upwardly on the lower end of the sleeve H¹⁷. This lifting tendency of the spring, however, in the downwardly moved position of the rod, will be resisted and overcome 55 by a rotary cam V rotatably mounted on the sleeve H¹⁷ at its upper end and arranged in position to engage a collar V¹ fixed to the rod H. When the cam V is set with its high point in contact with the collar V¹, it will, by reacting against 60 the collar and over the opposition of the spring h¹, hold the sleeve H¹⁷ in contact with the second collar h at the lower end of the rod. Under such a setting of the cam, as will now be evident, there can be no relative movement between 65 the rod and the sleeve, and the two parts function as if they were rigidly united, which is the condition that should exist when casting from lines without spacebands. On the other hand, when the cam V is set, say to bring its lowest point 70 into contact with the collar V¹, then the sleeve

H¹⁷ in the downwardly moved position of the rod H will be raised by the spring h¹ out of engagement with the collar h, and the clearance thus provided will determine the amount of the relative movement which can take place between the rod and sleeve after the locking of the latter by the toggle member J in the manner before described. This is a condition which should exist when it is desired to provide for a less spread of a composed line, the cam V is set in an intermediate position, that is to say in a position intermediate its lowest and highest points.

The cam V may be set either manually or automatically to allow for different degrees of line spread, depending upon the length of the composed line. The means for setting the cam V are described fully in the Frolander patent heretofore referred to and will not be repeated here. 15

The outward limited movement of the jaws E and F to allow for the line spread prior to justification is effected by positively raising the vertically movable rod H to the limited degree allowed by the setting of the cam V, it being recalled that the sleeve at this time is positively locked by the toggle member J. The mechanism for effecting the upward limited or line spread movement of the rod H is illustrated in Fig. 2. By reference to this figure, it will be seen that 20 the lever H³, which actuates the rod H, is provided with an upwardly extending bifurcated arm H¹⁸ having a pin H¹⁹ playing in a closed slot H²⁰ formed in the forward end of a fore-and-aft actuating link H²¹, the length of the slot being 25 such that the pin may travel from one end thereof to the other without affecting the link as the rod H is moved back and forth by the lever H³ between its uppermost and lowermost positions. As will presently appear, when the machine is in 30 operation, the link H²¹ is moved rearwardly after the sleeve H¹⁷ has been locked by the toggle member J in its downwardly moved position with the clamping jaws in contact with the composed line and, in its rearward movement, the link will sooner or later (depending upon the extent of the downward movement of the sleeve) engage the pin and, 35 through the arm H¹⁸, rock the lever H³ in a counter-clockwise direction against the opposition of the spring H⁷. This counter-clockwise 40 rocking movement of the lever is, of course, communicated to the rod H which, as a result, is moved upwardly with reference to the sleeve H¹⁷ until the rod collar h banks against the lower end of the sleeve, the extent of such relative movement of the rod being, as previously stated, determined by the setting of the cam V. It is this upward limited movement of the rod H which moves the line clamping jaws outwardly from their line 45 contacting position and thus determines the final quadding or centering position of the jaws when a composed line is to be spread or justified by the expansion of the contained spacebands. In Fig. 1, there is illustrated a condition wherein the machine is set for quadding at the right end of the line, and there the initial quadding positions of the right hand jaw F and its associated parts are shown in solid lines, the position which the jaw will assume after the line has been spread in the manner just described being shown in dotted 50 line.

Going back to the actuating connections, the link H²¹ is slidably supported in a bracket M² attached to the fixed machine frame and is connected by a long tension spring H²² (which is 55

more powerful than the spring H^7 above referred to) to the lower end of a lever H^{23} secured to and depending from a shaft H^{24} journalled in a supporting bracket M^3 attached to the fixed machine frame at the rear. Likewise secured to the shaft, in offset relation to the lever, is a second lever H^{25} having a forwardly extending arm which carries at its extremity a roller H^{26} arranged to cooperate with a cam M^4 . While this cam might be mounted directly on the shaft, it is, as a matter of convenience, attached to the side face of the cam M^1 which controls the jaw closing and jaw opening movements of the rod H .

As will be noted, the relation of the two cams M^1 and M^4 is such that shortly after the former has operated the lever H^{13} to effect the downward or jaw closing movement of the rod H and to lock the sleeve in its downwardly moved position, the cam M^4 will be caused to engage with the roller H^{26} and rock the connecting levers H^{23} and H^{25} clockwise to draw the link H^{21} rearwardly in effecting the limited upward movement of the rod H relatively to the locked sleeve H^{17} in the manner before described. The cam M^4 maintains its engagement with the roller, and hence, maintains the rod H in its limited raised position until after the composed line has been justified or spread by the expansion of the spacebands. Thereafter, the cam travels clear of the roller and the levers H^{23} and H^{25} are restored to their original or normal position of rest by a spring H^{27} connected to the lower end of the lever and pulling forwardly thereon from an anchorage point in the machine frame, a stop H^{28} engaged by the lever H^{25} serving to locate the parts in their proper positions. In order to move the link H^{21} forwardly to its original or normal position of rest, the link is provided with a long rod H^{29} extending through the spring H^{22} and connected at its rear end by a pin and slot H^{30} connection to the lever H^{23} . The play of the pin and slot connection H^{30} is such that the actuating movement of the lever H^{23} will always be transmitted to the link H^{21} through the spring H^{22} , the rod H^{29} therefore, acting merely as a return connection for the link from the spring. While unnecessary perhaps, the rod H^{29} is slidably supported at its forward end in a bearing formed in the bracket M^2 .

Upon the return movement of the link H^{21} , the spring H^7 again comes into play and tends instantly to rock the lever H^3 clockwise to move the rod H down again relatively to the locked sleeve H^{17} (it being noted that at this time the high portion of the cam M^1 is still in engagement with the roller H^{16} of the lever H^{13}) but if the line has been properly justified or spread out by the spacebands to the full extent permitted by the outward movement of the jaws from their line contacting position, the line itself will serve to prevent such return movement of the rod by the spring H^7 . On the other hand, if for any reason the line has not been fully expanded by the spacebands, so as to fill out the space between the jaws, the rod H can and will be moved downwardly by the spring H^7 to whatever extent it is required to close the jaws upon the composed line. In this latter event, which is an abnormal operation, the return downward movement of the rod H is utilized to prevent the casting operation from taking place.

As thus far described, the parts and their operation, except as hereinafter noted, are or may be the same as set forth in the Frolander Patent No. 1,971,400, before referred to.

It will be recalled now that this invention aims to effect a slight outward or backing away movement of the jaws E and F from the line after the casting operation has taken place in order to relieve the pressure on the line prior to the time that the line is raised by the first elevator A from between the jaws. Accordingly (see Fig. 5), the toggle operated clamp or grip member J^1 that engages the sleeve H^{17} is formed in its sleeve engaging surface with teeth J^8 adapted to engage corresponding teeth h^2 on the sleeve in order that this engagement may be a positive one instead of relying solely upon pressure, as in the Frolander patent previously referred to. Furthermore, it will be noted that in the normal position of the toggle clamp J^1 , there is a small clearance or gap J^9 between the top of the clamp and the top plate B^3 of the toggle clamp housing B^2 , which is approximately ten thousandths of an inch. This is maintained, except under conditions hereinafter noted, by a shoe B^4 (see Fig. 8) pivotally mounted in the top plate B^3 and formed in its lower edge with a cam surface B^5 , which is pressed against the clamp J^1 by a spring b fastened to an offset portion of the shoe and anchored in the top plate B^3 . When the vertically movable rod H and the sleeve H^{17} are arrested in their downward movement by the banking of the jaws against the ends of the composed line, the continued movement of the lever H^9 will draw down on the link J^2 and will operate the toggle member J in the manner before described to press the clamp J^1 into engaging relation with the sleeve H^{17} so as thereby to lock the sleeve in its downwardly moved position, but it will be noted that in this case the toggle member J is forced beyond the dead center position (see Fig. 5).

As shown in Fig. 9, there is another vertically movable link K pivotally connected at its lower end to the lever H^9 , and which is constrained to move in a vertical direction by a protruding portion B^6 of the toggle member housing top plate B^3 that projects into an elongated slot K^1 in said link, the link being held against separation from the projecting member by a washer and screw threaded into the projecting portion of the plate just alluded to. The link K is pulled downwardly by the lever H^9 as the latter moves to effect the operation of the toggle member J and, when it reaches its lowermost position (see Figs. 1 and 2), an adjustable set screw K^2 threaded into a horizontal offset portion at the top of the link K engages the shoe B^4 at the top and through the shoe, positively holds the clamp J^1 in its lowermost position against any tendency of the clamp to rise during the spreading of the jaws prior to justification and during the justification of the line itself, it being obvious that if the clamp were not thus positively held, the upward movement of the rod to effect the spreading movement of the jaws would raise the clamp to close the gap J^9 , as would also the expansion of the line during justification, the upward thrust of the spacebands in the latter instance acting to separate the line clamping jaws, which in turn would lift the rod and sleeve and consequently the clamp.

About centrally of its length, the link K is also formed with a rearwardly projecting lug K^3 , into which there is threaded an adjustable banking screw K^4 and, as the link K is moved downwardly in the manner before described, this screw will engage at the center of a lever L , pivotally mounted at its right end in the base of the fixed housing

B², to effect the extension of a relatively strong spring L¹ fastened at its lower end to the left end of the lever L (see Fig. 1) and anchored at its upper end in a fixed part of the machine (see Fig. 2).

After the casting operation has been completed, the roller H¹⁶ rides off the high portion of the cam M¹ and, as it does so, the lever H⁹ will act to raise both the link J² and the link K, thus releasing the shoe E⁴ that holds the clamp J¹ in its lowermost position and the lever L, just mentioned. The screw J³ at the top of the link J² will also move away from the toggle member J, but the latter will not operate to release the clamp, since, as previously stated, it was urged past its dead center position, and the spring J⁶, that ordinarily tends to release it, is not strong enough to force it back beyond the dead center position. Consequently, with the clamp J¹ still engaging the sleeve H¹⁷, the lever L is swung from the position shown in Fig. 1 to the position shown in Fig. 10 and, in so doing, a cam surface l formed on the upper edge of the lever near its pivot point will engage the lower end of a vertically movable pin L² slidably arranged in the bottom portion of the toggle member housing B² beneath the clamp J¹ and cause said pin to force the clamp upwardly to close the gap J⁹ between it and the top plate B³. As the clamp J¹ moves upwardly, it will carry with it the sleeve H¹⁷. The rod H will follow under the action of the spring H¹⁵, and this upward movement of the rod will be sufficient to back the jaws E and F away from the line a distance sufficient to relieve the clamping pressure thereon,—approximately $\frac{1}{2}$ of an inch for a gap of ten thousandths of an inch between the clamp and plate referred to before.

Actually in some cases, as for instance when quadding a long line, the means just described for effecting the upward movement of the toggle clamp J¹ might not be necessary, since, under such circumstances, the lost motion between the levers H³ and H⁹ is relatively large. When the lost motion is large, the lever H⁹ will gather considerable momentum in its return movement under the influence of the spring H¹⁵, and the force with which the lug H¹⁰ thereon will strike the lug H¹¹ on the lever H³ should and probably would be sufficient to force the rod H and the clamp J¹ upwardly through the limited distance provided by the gap J⁹. However, when quadding a short line, the lost motion being substantially smaller might not be sufficient to allow the lever H⁹ to gather the necessary momentum in its return movement to effect the limited jaw separating movement of the rod H when it is held by the clamp J¹, and it is for this reason that the supplemental means for raising the clamp J¹ and the rod H is provided.

The jaws E and F will be held in their positions of limited separation, i. e., slightly backed off from the line until after the rod H has been released by the toggle clamp J¹, despite the fact that the roller H¹⁶ on the arm H¹³ that actuates the levers H³ and H⁹ passes off the high portion of the actuating cam M¹. Indeed, the roller actually loses contact with the cam for a portion of the machine cycle or until after the toggle clamp has been released.

The toggle lock J is released and the clamp J¹ disengaged from the sleeve H¹⁷ to allow the jaws E and F to return to their positions of maximum separation when the first elevator has ascended almost to its uppermost position, and the mechanism for effecting such release of the toggle lock

will now be described. It will be noted that the front bearing block J¹⁰ of the toggle member is arranged for a slight fore-and-aft movement, and is normally held in its rearward position by a stud J¹¹, against which the block banks. This stud, as shown clearly in Fig. 7, is provided with a sleeve J¹² formed at its inner end with a head or flanged portion J¹³, and at its outer end with a reduced portion J¹⁴, the purpose of which will be noted presently. The front face of the flange J¹³ is formed with two diametrically opposed high portions J¹⁵ and two intermediate low portions J¹⁶, and these high and low portions are adapted to cooperate with a pair of protruding lugs J¹⁷ formed on a small plate J¹⁸ (Figs. 5 and 6) fastened at the inner face of an L-shaped block B⁷ that constitutes a part of the front wall of the toggle member housing B², and which also presents the upper guiding surface for the front toggle block J¹⁰, the lower guiding surface being presented by another portion of the front wall of the housing. When the stud J¹¹ is turned to bring the high portions J¹⁵ of the flange in registry with the protrusions J¹⁷ on the plate J¹⁸, which incidentally is the normal position of the parts, the front toggle block J¹⁰ will be in its rear-most position, wherein the toggle will be held in its position below dead center. However, when the stud is turned to bring the low portions J¹⁶ of the flange into registry with the protrusions J¹⁷ on the plate J¹⁸, the stud J¹¹ will be allowed to move forwardly for a limited distance, as determined by the depth of said low portions, and this movement will be sufficient to allow the spring J⁶ to force the toggle upwardly past the dead center position and withdraw the clamp J¹ out of engagement with the sleeve H¹⁷; the sleeve, and consequently the rod H, thus being freed and allowed to ascend to normal position, and in so doing, move the jaws to their positions of maximum separation. It might be stated here that the outward movement of the jaws E and F after the sleeve H¹⁷ has been released will be rather rapid, since at this time the roller H¹⁶ will have left the high portion of the cam and, in order to prevent banging and possible breakage of the parts, the lever H⁹ may be equipped with a dash pot, if desired, to slow up the motion, although one is not shown in the drawings.

The stud J¹¹ is located in its different positions by a swivel plate N held on the reduced portion J¹⁴ of the stud by a nut N¹ threaded on the end thereof. As shown in Figs. 1 and 5, this swivel plate has a downwardly extending portion N² which, in the normal position of the parts, banks against a fixed portion of the vise frame and is retained in such position by a tension spring N³ fastened to an upwardly projecting portion N⁴ formed on the plate and having an anchorage likewise in the vise frame. The normal position of the swivel plate corresponds to that position of the stud, wherein the high portions of the flange register with the protrusions J¹⁷ on the plate. However, when the first elevator nears the upper end of its stroke, a pin a located near the lower end thereof will engage a lip N⁵ projecting forwardly from the swivel plate, causing the latter to swing in a counter-clockwise direction to turn the stud J¹¹, so as to locate the low portions J¹⁶ of the flange thereon in registry with the protrusions J¹⁷; and when this occurs, the toggle member releases the sleeve H¹⁷ and allows the jaws to be returned to their positions of maximum separation. The location of the pin a in the first elevator is such that it will not travel

upwardly past the swivel plate, but only far enough to swing the plate through a distance sufficient to effect the release of the toggle member in the manner previously described. When the elevator A descends to its normal line receiving level, the swivel plate N, and consequently the stud J¹¹, will be returned to normal position under the action of the tension spring N³, previously mentioned. It should be noted, perhaps, that although the toggle release spring J⁶ is not sufficiently strong to force the toggle member upwardly past dead center when the stud J¹¹ is in its normal position, there is sufficient give in the parts to allow the toggle member to be forced past dead center in a downward direction, this latter operation of course, being effected through positive connections from the main shaft of the machine, all as previously described.

In the accompanying drawings the invention has been shown merely by way of example and in preferred form, and obviously many variations and modifications may be made therein which will still be comprised within its spirit. It is to be understood, therefore, that the invention is not limited to any specific form or embodiment, except insofar as such limitations are specified in the appended claims.

Having thus described my invention, what I claim is:

30. 1. A slug casting machine including, in combination, a pair of line clamping jaws movable one toward the other in quadding, mechanism for effecting such quadding movement of the jaw, and means acting to effect a limited separating movement of the jaw after casting to relieve the pressure on the line and for preventing full separating movement of the jaw until after the composed line has been withdrawn from between the jaws.

40. 2. A slug casting machine including, in combination, a pair of line clamping jaws movable one toward the other in quadding, mechanism for effecting such quadding movement of the jaw and for effecting a separating movement of the jaw after the casting operation to return the parts to normal position, and means acting through said mechanism to relieve the pressure on the line after casting while preventing the full separating movement of the jaw until after the composed line has been withdrawn from between the jaws.

50. 3. A slug casting machine including, in combination, a pair of line clamping jaws movable one toward the other in quadding, mechanism including a vertically movable rod for effecting such quadding movement of the jaw and for effecting a separating movement of the jaw after casting to return the parts to normal position, means for arresting the rod after a limited separating movement of the jaw to relieve the pressure on the line and until after the line has been withdrawn from between the jaws, and means for thereafter releasing the rod to permit the full jaw separating movement thereof.

60. 4. A slug casting machine including, in combination, a pair of line clamping jaws movable one toward the other in quadding, a line transporter for presenting a composed line between the jaws for casting, mechanism for effecting such quadding movement of the jaw and for effecting a separating movement of the jaw after casting to return the parts to normal position, means acting to limit the separating movement of the jaw to an extent sufficient to relieve the pressure on the line until after the line has been

withdrawn from between the jaws, and means controlled from the line transporter for operating said limiting means to permit the separating movement of the jaw to be completed.

5. A slug casting machine including, in combination, a pair of line clamping jaws movable one toward the other in quadding, a line transporter for presenting a composed line between the jaws for casting, mechanism for effecting such jaw quadding movement of the jaw and for effecting a separating movement of the jaw after casting to return the parts to normal position, means acting through said mechanism to limit the jaw separating movement to an extent sufficient to relieve the pressure on the line until after the line has been withdrawn from between the jaws, and means controlled from the line transporter for operating said limiting means to permit the separating movement of the jaw to be completed.

10. 6. A slug casting machine including, in combination, a pair of line clamping jaws movable one toward the other in quadding, a line transporter for presenting a composed line between the jaws for casting, mechanism including a vertically movable rod for effecting such quadding movement of the jaw and for effecting a separating movement of the jaw after casting to restore the parts to normal position, and means for arresting the rod after a limited separating movement of the jaw sufficient to relieve the pressure on the line and until after the line has been withdrawn from between the jaws, and means controlled from the line transporter for thereafter releasing the rod to permit the full separating movement of the jaw.

15. 7. A slug casting machine including, in combination, a pair of line clamping jaws movable one toward the other in quadding, mechanism including a vertically movable rod for effecting such quadding movement of the jaw and for effecting a separating movement of the jaw after casting to return the parts to normal position, means for locking the vertically movable rod in its jaw quadding position during the casting operation, means for allowing a limited jaw separating movement of the rod to relieve the pressure on the line after casting, and means for releasing the rod after the line has been withdrawn from between the jaws to permit the separating movement of the jaw to be completed.

20. 8. A slug casting machine including, in combination, a pair of line clamping jaws movable one toward the other in quadding, mechanism for effecting such quadding movement of the jaw, means for presenting a composed line of matrices and expansible spacebands between the line clamping jaws, means for expanding the spacebands after a quadding operation to fill out the space between the jaws, and means acting after a casting operation to effect a limited separating movement of the jaw to relieve the pressure on the line and to maintain the jaw against full separating movement before the line has been withdrawn from between the jaws.

25. 9. A slug casting machine including, in combination, a pair of line clamping jaws movable one toward the other in quadding, mechanism for effecting such quadding movement of the jaw, means for presenting a composed line of matrices and expansible spacebands between the line clamping jaws, means for expanding the spacebands after a quadding operation to fill out the space between the jaws, means acting after a casting operation to effect a limited separating movement of the jaw to relieve the pressure on the line until after the line has been withdrawn from between the jaws.

the line, and devices operative after the line has been withdrawn from between the jaws to allow the separating movement of the jaw to be completed.

5 10. A combination according to claim 9, wherein in the composed line is presented between the jaws by a vertically movable line transporter, and wherein the devices for allowing the separating movement of the jaw to be completed are controlled from said line transporter.

10 11. A slug casting machine including, in combination, a pair of line clamping jaws movable one toward the other in quadding, mechanism including a vertically movable rod for effecting such quadding movement of the jaw, devices for locking the rod in a position determined by the contact of the jaw with the line, means operating while the locking devices are active and after casting to move the rod to effect a limited separating movement of the jaw to release the pressure on the line, and means for thereafter releasing the locking devices to allow the jaw to be returned to normal position.

15 12. A slug casting machine including, in combination, a pair of line clamping jaws movable one toward the other in quadding, mechanism for effecting such quadding movement of the jaw and including a vertically movable rod, means including a toggle lock for holding the vertically movable rod in a position determined by the contact of the jaw with the line, means for moving the rod a limited distance after casting to effect a slight separating movement of the jaw to relieve the pressure on the line, and means for thereafter releasing the toggle lock to allow the jaw to be returned to normal position.

20 13. A slug casting machine including, in combination, a pair of line clamping jaws movable one toward the other in quadding, mechanism for effecting such quadding movement of the jaw and including a vertically movable rod, a vertically movable line transporter for presenting a composed line between the jaws, means including a toggle lock for holding the vertically movable rod in a position determined by the contact of the jaw with the line, means for moving the rod a limited distance after casting to effect a slight separating movement of the jaw to relieve the pressure on the line, and means controlled by the line transporter for releasing the toggle lock to allow the jaw to be returned to its normal position.

25 14. A slug casting machine including, in combination, a pair of line clamping jaws movable one toward the other in quadding, mechanism for effecting such quadding movement of the jaw, means for moving the jaw before casting a limited distance away from the line to permit justification, means other than the line itself for moving said jaw a limited distance away from the line after casting to relieve the pressure thereon, and means for holding the jaw in such position until after the line has been withdrawn from between the jaws.

30 15. A slug casting machine including, in combination, a pair of line clamping jaws movable one toward the other in quadding, mechanism for effecting such quadding movement of the jaw, said mechanism including a vertically movable rod, means for actuating said rod before casting to move the jaw a limited distance away from the line to permit justification, means for actuating

said rod after casting to move the jaw a limited distance away from the line to relieve the pressure thereon, and means for holding the rod in such position until after the line has been withdrawn from the jaws.

5 16. A slug casting machine including, in combination, a pair of line clamping jaws movable one toward the other in quadding, mechanism for effecting such quadding movement of the jaw, a vertically movable line transporter for presenting a composed line between the jaws, means for moving the jaw before casting a limited distance away from the line to permit justification, means other than the line itself for moving said jaw after casting a limited distance away from the line to relieve the pressure thereon, and means controlled from the line transporter for thereafter permitting the return of the jaw to normal position.

10 17. A slug casting machine including, in combination, a pair of line clamping jaws movable one toward the other in quadding, mechanism for effecting such quadding movement of the jaw, said mechanism including a vertically movable rod, a vertically movable line transporter for presenting a composed line between the jaws, means for actuating said rod before casting to move the jaw a limited distance away from the line to permit justification, means for actuating said rod after casting to move the jaw a limited distance away from the line to relieve the pressure thereon, and means controlled from the line transporter for thereafter releasing the rod to allow the return of the jaw to normal position.

15 18. A slug casting machine including, in combination, a pair of line clamping jaws movable one toward the other in quadding, mechanism for effecting such quadding movement of the jaw, said mechanism including a vertically movable rod, means comprising a toggle operated clamping block for holding the rod in different positions as determined by the quadding movement of the jaw, said block being arranged for limited movement while in rod holding position, means acting after a casting operation to move the rod under the control of the block to relieve the pressure on the line, and means for thereafter rendering the clamping block inactive to allow the rod to return the jaw to normal position.

20 19. A slug casting machine including, in combination, a pair of line clamping jaws movable one toward the other in quadding, mechanism including a vertically movable rod for effecting such quadding movement of the jaw, a line transporter for presenting a composed line between the jaws, means including a toggle operated clamping block for holding the rod in a position determined by the contact of the jaw with the line, said clamping block being arranged for limited movement while in rod holding position, means acting after a casting operation to move the rod under the control of the block to relieve the pressure on the line, and means controlled from the line transporter for thereafter rendering the clamping block inactive so as to allow the rod to return the jaw to normal position.

25 20. A combination according to claim 19, wherein means supplementary to the rod actuating mechanism are provided to act directly upon the clamping block itself for moving the rod after casting to relieve the pressure on the line.

RICHARD R. MEAD.
